UNITED STATES PATENT OFFICE.

JOHN P. STEPPE, OF NEW YORK, N. Y., ASSIGNOR TO S. STERNAU & CO.,
OF SAME PLACE.

DESIGN FOR A CHAFING-DISH STAND.

SPECIFICATION forming part of Design No. 31,666, dated October 17, 1899.

Application filed September 11, 1899. Serial No. 730,175. Term of patent 3½ years.

To all whom it may concern:

Be it known that I, JOHN P. STEPPE, a citizen of the United States, residing at New York, borough of Brooklyn, county of Kings, and State of New York, have invented and produced a new and original Design for Chafing-Dish Stands, of which the following is a specification, reference being had to the accompanying drawings, forming a part thereof.

Figure 1 is a perspective view of a chafing-dish stand, showing my new design. Fig. 2 is a sectional view of the top ring, taken on the line 2 2 of Fig. 1. Fig. 3 is a sectional view of one of the legs or standards, taken on the line 3 3 of Fig. 1.

The leading or characteristic feature of my design consists of the shape or outline of the several parts going to make up the complete stand, the supporting - ring being round in cross-section, the legs or standards being also round in cross-section and tapering from their upper to their lower ends, ending in feet in the form of spheres, the lower smaller lamp-supporting ring being flat on its inner surface and rounded or curved on its outer surface, and the brackets, which connect said lower ring to the legs or standards, being round in

cross-section where they join the lower ring and flattened on their outer ends, where the legs or standards pass through them.

Referring to the drawings, A represents the upper or supporting ring, which is round in cross-section, as shown in Fig. 2, and B the legs or standards, which are also round in cross-section, as illustrated in Fig. 3, and which taper from their upper ends to their lower ends, where they end in the spherical feet C.

D is the lamp-supporting ring, and E the brackets, which connect said latter ring to the legs or standards B, said brackets being rounded in cross-section where they join the ring D and somewhat flattened at their outer ends F, where the legs or standards pass through them.

Having fully described my invention, what I claim as new, and desire to secure by Letters Patent, is—

The design for a chafing-dish stand, substantially as herein shown and described.

JNO. P. STEPPE.
